PULL-OVER GARMENT

George K. Manus, Los Angeles, Calif.

Application December 1, 1943, Serial No. 512,671

1 Claim. (Cl. 2—115)

1

My invention relates to garments of the sports type and more particularly to garments designed to be put on by the wearer pulling them over his head and so known as "Pull over." Such garments are generally of the loose knit fabric type and make little or no attempt to hang or drape particularly well, but my invention is designed to provide a garment which, in contrast to such loose knit fabric type, may be made from any material and are designed to "drape" or mould to the wearer's torso as well as shirt or coats of the usual kind having a neck opening which may be closed by buttons or "zippers," but I achieve this effect without fastening means of any kind.

An object of my invention is to provide a "pull-over" garment designed to "drape" or fit well on the torso of the wearer.

Another object of my invention is to provide a "pull over" garment which is easy to launder and iron by reducing extra pieces or layers of cloth to a minimum.

A still further object of my invention is to provide a "pull over" garment having a collar in one piece with the shoulder and chest and front portions of the garment.

A still further object of my invention is to provide a "pull over" garment made up with side pieces which may be of different material and of different color to the neck shoulder and front part of the garment, enabling additional fashioning to shape to be provided as well as enabling pleasing contrasting or blending of colours and/or texture of material to be provided.

A still further object of my invention is to provide a garment of simple construction which can be quickly and accurately made up by semi-skilled help by the use of the simple patterns permitted by the cut of the garment.

Various other objects and features of the invention may hereinafter appear from the following specification and accompanying drawings. In the drawings, in which identical numerals indicate identical parts.

Fig. 1 is a view of the cut out piece of material forming the collar, neck, shoulder and front of my pull over garment with side pieces shown detached.

Fig. 2 is a pictorial view of the garment in position on the wearer.

Fig. 3 is a pictorial view of the garment showing the neck opening enlarged to permit the wearer to pull the garment over his head.

Referring now to Fig. 1, the piece of material forming the collar, shoulders and front of the garment is indicated generally by the numeral 10.

2

This piece of material comprises an upper portion forming the collar 12, one shoulder portion 14, an opposite shoulder portion 16 and cross over piece 22, and a downwardly extending front portion 20 depending from the shoulder portion 14. A generally triangular opening is formed in the material as indicated at 18 by cutting along the lines 13a, 15, 17.

It is pointed out that while the area of the material at the upper portion of the blank forming both shoulders is identical, the front 20 is formed from the piece of material depending from the shoulder area at one side only, as shown.

Depending from the material forming the shoulder area on the opposite side to the front piece, is the cross over piece 22 which extends downwardly to a distance sufficient only to fold over the upper chest area as will be later described. As will be seen from Fig. 2 the cross over piece 22 is arranged to lie below the front piece 20 as indicated by the dotted lines in this figure. The top lines 11, 13 of the cut out piece of material to each side of the collar portion 25 form a diagonal line extending downwardly over the upper front of the assembled garment from the front of the collar to the level of the opposite arm pit, while the lines 15 and 17 form the top seam of the shoulders when the cut out material is folded.

While the parts of the garment just referred to may form a unitary piece I may prefer to cut them in the form of two pieces, the division line being indicated at 26. Further, while the sides 35 as well as the front of the garment may be formed from the same piece of material I prefer to obtain side pieces 28, 30 by cutting along the curved lines 32, 34 which provides the front half of the arm holes formed in the sides of the garment, and along the lines 36, 38 which defines the back vertical edge of the side pieces, and along the lines 40, 29, and 42 which define the front vertical edges of the side pieces. I prefer to form the sides of the garment as separate panels of 45 different coloured material or material of different texture, thus by cutting several layers of cloth of desired colors and/or materials as explained I can obtain the parts required to make up garments in a plurality of combinations of 50 material and color of shoulder and front with sides of the same material and color or of different material or color, and further, by trimming the side pieces or vertical edges of the parts I can more fully shape the garment to 55 the individual who is to be fitted.

In explaining the assembling of the pieces cut according to the pattern described it will be assumed that a garment having side pieces of different coloured material is to be made, and that a unitary piece of material is used.

I prefer to first complete collar 12 by facing it with material in the usual manner, and next the side pieces 28, 30, which were cut from another piece of cloth but to the identical pattern, are sewn along the lines 29, 40, 42 which will constitute the front vertical side seams of the garment. The cross over or chest piece 22 is then folded inward, and downward to bring the point 24 to the point 24a which is on the side vertical seam of the opposite side of the front 20. The full front piece 20 is then folded over the piece 22, the fold being arranged so that the point 21 lies on point 23 on the side vertical seam opposite to point 24a. The step described will cause the bottom line 25 of the cross over piece to lie along the dotted line indicated in Fig. 2, but the cross over piece 22 is not sewn along this bottom line to piece 20 but only connected to the front 20 by sewing point 24 to 24a. Lines 17 and 15 at the sides of the opening 18 are then smoothed out to extend horizontally to form the top seam of the shoulders. The points 24 and 21 are sewn in the positions stated and the free edge 27, of the front of the garment is sewn to the edge 40, 29. The back of the garment is then completed in the known manner by sewing a piece of material along one edge to the bottom edge 13a of the collar and top shoulder seams 15, 17, and to the vertical seams 36, 38, the back half of the arm holes corresponding to the front part arm holes 32, 34, being cut in this piece of material. If sleeves are to be attached they are fitted in the known manner. These sleeves may be of course of any length desired.

Patch pockets are finally added if desired and as shown in Fig. 2, are preferably positioned so as to cover the point at which the diagonal lines of the top of the assembled garment are secured to the side seams.

The advantage of the garment of my invention is due to the ability of the neck of the garment to open widely when the sides of the collar are pulled apart, this being due to the attachment of the folded over front at two widely spaced points only, enabling the garment to give freely. However, when the garment has been put on, the weight of the garment and the diagonal arrangement of the upper part of the garment causes the collar opening to fit neatly around the wearer's neck.

The forming of the garment from a number of separate pieces also aids in ensuring a well fitted garment which drapes or hangs becomingly on the wearer.

A further important advantage is that the front of the garment is clear of sewn seams between the neck opening and the bottom of the front, and from one front side seam to the opposite front side seam, this facilitates laundering, and especially ironing, the garment.

It will be seen by reference to the preferred form of my invention in the drawings that I have provided a well fitted and complete garment having good chest space, with a neat fit around the waist and room over the hip, providing an exceptionally good looking and comfortable garment, yet one easily cut to fit various types of figure or fitted to the individual user.

I may prefer to allow material for the sides at the outer edges of the garment instead of at the inner and may leave the material in this case in one piece, but have secured very satisfactory results from the garment made as herein shown.

While I have described and shown in the drawings a preferred embodiment of my invention it will be apparent to those skilled in the art that various modifications may be made in the cutting and making of the garment without departing from the scope of the invention as defined by the appended claim.

I claim:

In a pull over garment comprising a collar portion surrounding a neck opening, shoulder portions, inner and outer cross over chest portions and a back portion; a full length front portion formed as an extension of the outer cross over chest portion, a first side panel secured along the whole length of one of its edges to the whole length of one vertical edge of the outer cross over chest portion, a second side panel secured along the whole length of one of its edges to the other vertical edge of said outer cross over chest portion and to the vertical edge of the inner cross over portion, both said side panels being provided with front part arm holes, the top front of the garment being defined by the upper edges of the inner and outer cross over chest portions each of which run diagonally from the front of the neck opening at one side downward and across to the vertical seam at the opposite side between the chest portion and side panel and are secured to the garment only at said side seams at about arm pit level leaving the lower edge of the inner cross over portion free from the outer cross over portion across the chest between said vertical seams, the back portion being connected to the free edges of the side panels and back of the shoulder and collar portions.

GEORGE K. MANUS.
